CHESTER H. THORDARSON, OF CHICAGO, ILLINOIS.

METHOD OF PRODUCING ELECTROMAGNETIC COILS.

1,165,558.

Specification of Letters Patent.

Patented Dec. 28, 1915.

Application filed January 11, 1915. Serial No. 1,704.

To all whom it may concern:

Be it known that I, CHESTER H. THORDARSON, a citizen of the United States, and a resident of Chicago, in the county of Cook and State of Illinois, have invented certain new and useful Improvements in Methods of Producing Electromagnetic Coils; and I do hereby declare that the following is a full, clear, and exact description thereof, reference being had to the accompanying drawings, and to the characters of reference marked thereon, which form a part of this specification.

This invention relates to a novel method of producing flat wire electro-magnetic coils or windings for transformers and other electro-magnetic devices, and the invention consists in the matters hereinafter set forth and more particularly pointed out in the appended claims.

An object of the invention is to reduce the cost of producing such coils and to reduce the dimensions of the coil produced as compared to its capacity for work.

Another object of the invention is to provide an improved method of producing coils, whereby such coils may be made up of extremely thin and narrow flat wires without involving complications in handling the wire in the different stages of the manufacture of the coil.

In producing a coil in accordance with my novel method I apply to a sheet or web of electrically conductive metal of the required gage, and of a substantial width to produce a number of flat wires, a thin insulating coating which, (for some metals may consist of an oxid formed on the sheet, and for others of an enamel applied thereto); thereafter slitting the said sheet into narrow strips of a width to produce the resultant flat wires; thereafter winding the flat wires thus produced into a coil, and thereafter treating or conditioning the end faces of the coil, formed by the edges of the flat wire, so as to remove or avoid sharp projections or burs formed on said edges when cutting the sheet to produce the flat wires, and thereby avoiding short circuiting between the turns.

In some instances, the conditioning of the end faces of the coil may be effected by an acid of such character as to cut back into the metal of the flat wire at the exposed sides thereof, while being neutral to the insulating covering, so as to leave, in effect, between the turns overhanging insulating ledges con-

sisting of the edges of thin oxid or enamel coating. In other instances, the burs or roughened edges may be covered by an insulating coating to avoid short circuiting 60 between the turns.

An oxid coating may be applied to the sheet by passing the sheet through an electrolytic bath of proper solution while subjected to the charge of an electric current. 65 The enamel may be applied in the usual way, as by passing the sheet through an enamel bath to coat the sheet and subsequently passing the coated sheet through an annealing chamber. By reason of the capillary effect between the liquid of the electrolytic or enamel bath and a strip or sheet of metal to be coated, the insulating coating tends to accumulate at the edges of the strip or sheet so as to thereby substantially 70 thicken the coated sheet or strip at its margins. For this reason it becomes impractical to coat flat wires of the ultimate width required for the coil inasmuch as the thickened margins prevent the flat wire being 75 made into compactly and symmetrically wound coils.

In the practice of my improved method for producing coils the edges of the coated sheet are sheared off at or before the time 85 the sheet is being cut into strips, so that the remaining portion of the sheet from which the flat wires are cut is of uniform gage throughout and may be compactly and symmetrically wound into a coil. Furthermore, 90 it is quite impracticable, if not commercially impossible, to apply such insulating coating to very thin and narrow strips or wires, say of .0003 of an inch in thickness and from $\frac{1}{2}$ to $\frac{1}{4}$ of an inch in width, by 95 reason of the mechanical difficulties which are encountered in passing such thin delicate strips through the coating bath and winding them into a coil. This mechanical difficulty of handling the material is not encountered when the coil is produced by my improved method, for the reason that the sheet itself is of such width as to be readily passed through the coating bath, and said sheet may be readily cut up into strips and 100 the strips wound into coils. However, regardless of the gage and width of the flat wire, the expense of producing same by my novel method is materially reduced by reason of the greater facility of handling the 105 material. In some instances I may wind the strips into coils directly from the cut-

ting machine, while in other cases I may wind the strips into rolls which are thereafter unrolled and wound into coils.

I have illustrated in the drawings the various steps and stages of my novel method.

In said drawings:—Figure 1 illustrates a web or sheet which is first subjected to the coating bath and afterward cut to produce the flat wire or strips. Fig. 2 is a perspective view of a coil, partially wound, produced from the flat wire cut from the sheet shown in Fig. 1. Fig. 3 is an enlarged cross section of one of the coated flat wires produced by my novel method. Fig. 4 is a similar cross section of a coated flat wire which has been coated after being cut to its final width. Fig. 5 is an enlarged cross section of a number of turns of the coil before the end faces thereof have been conditioned. Fig. 6 is a similar view after the end faces have been subjected to the conditioning process.

The sheet 10, shown in Fig. 1, may be of any suitable width to produce, when cut, a number of resultant flat wires or strips 11. After the sheet has been subjected to a coating bath to apply an insulating coating thereto the side edges 12, 12 which, as before stated, are slightly thicker than the remaining portions of the sheet are sheared off. Preferably, in the practice of my novel method, the side edges of the sheet are sheared off at the same time the sheet is cut or split into strips to form the flat wires. Thereafter the coated flat wire is wound to produce the coil 13, shown in Fig. 2.

Fig. 3 shows a cross section of one of the flat wires 11 and also the insulating coating 14 thereon. It will be noted that the thickness or gage of the flat wire is uniform throughout the width of the wire. In comparing the flat wire 15 shown in Fig. 4 (which latter, it is assumed, has been coated as an individual wire) with the flat wire 11 shown in Fig. 3, it will be noted that in the former figure the coating solution has collected along the edges in a manner to produce on both sides thereof thickened portions 16, substantially thicker than the body 17 of the flat wire, so that it becomes impracticable to compactly wind such a wire into a coil with all parts of the turns laid flat upon each other, or to insure an assemblage of the flat wires in a coil with the edges flush to produce smooth end faces, inasmuch as the thickened portions will tend to cause the turns to slip or slide sidewise upon each other and produce irregular or unsymmetrical coil end faces.

The flat wires or strips may be cut from the sheet by a suitable cutting machine adapted for this purpose, and the wires so produced may pass directly from the cutting machine to the coil winding machine, or they may be primarily formed into rolls and the

rolls thereafter unwound and rewound into coils.

I may employ for flat wires any suitable metal having a high co-efficient of electrical conduction, such as copper, aluminum or the like. When using aluminum or like metal, the insulating coating may be produced thereon by passing the sheet through an electrolytic bath containing borax, a bath containing sodium phosphate or a bath containing sodium potassium tartrate, to form a thin oxid coating on the surface of the sheet. Such an oxid coating may be produced extremely thin while possessing high insulating efficiency. For instance, when employing a flat wire of .0003 of an inch in thickness the coating on each side need not exceed .0001 of an inch. It will thus be observed that the flat wire may be wound in a very compact coil or winding structure so as to thereby reduce the dimensions of the coil, and also reduce its weight as compared to its electro-magnetic efficiency.

When employing copper as a metal to produce the flat wire I may coat the sheet with a suitable enamel having the required degree of thinness and at the same time possessing the required insulating efficiency. After the coil has been wound, the end faces thereof present somewhat the appearance illustrated in Fig. 5, with the edges of the flat wire slightly roughened or burred due to the action of the cutting tools thereon during the cutting operation. Such roughened edges are objectionable in the coil inasmuch as they form discharge points across which the turns of the coil are liable to short circuit. The end faces of the coil may be conditioned to avoid such roughened edges of the flat wire either by coating the said faces with an insulating material to thereby insulate the turns from each other, or such conditioning may be effected by means of an acid of such character that when applied to the end faces of the coil it acts to cut the side edges of the flat wire slightly back from the planes of the said faces but which has no effect on the insulating coating. When using aluminum as the flat wire material, provided with an oxid insulating coating, I may treat the edges of the wire to produce the result described by the use of a solution of diluted hydrochloric acid. After the edges of the wire have been thus treated the edges of the insulating coating, which have not been affected by the conditioning process, overhang the wire edges to produce insulating ledges 17 which avoid short circuiting between the turns of the winding across said edges. Thereafter the end faces of the coils may be treated to a coat of thin insulating material, such as shellac, which may be applied by a brush or by dipping the coil in the shellac, or like solution.

When using copper wire coated with an

insulating enamel I may employ for the purpose of conditioning the end faces of the coil any suitable acid which will cut the copper but which is neutral to the enamel such, for 5 instance, as diluted nitric acid.

An advantage of the coil produced by my novel method in its use in a transformer, for instance, is that the edges of the flat wire may be very efficiently exposed to a 10 circulating coating medium whereby overheating of the wire under heavy service is avoided.

I claim as my invention:—

1. The method of producing electro-magnetic coils, which consists in applying to a 15 sheet of electrically conductive metal an insulating coating, thereafter shearing the thickened edges from the sheet and cutting the sheet into strips to produce flat wire conductors, and finally winding the flat wires 20 thus produced into a coil.

2. The method of producing electro-magnetic coils which consists in applying to a sheet of electrically conductive metal an insulating coating, thereafter cutting the sheet 25 into strips to produce flat wire conductors, thereafter winding the flat wire thus produced into a coil and finally treating the end faces of the coil to insulate the winding turns from each other at said end faces.

30 3. The method of producing electro-magnetic coils which consists in passing a sheet of electrically conductive metal through a bath to form thereon an insulating coating, shearing the thickened edges from said 35 sheet, and cutting said sheet into strips to produce flat wire conductors, winding the flat wire thus produced into a coil, and finally conditioning the end faces of the coil to insulate the winding turns from each 40 other at said end faces.

4. The method of producing electro-mag-

netic coils which consists in treating a sheet of electrically conductive metal to form thereon an insulating coating, cutting said sheet into strips to produce flat wire conductors, winding the flat wire thus produced into a coil and treating the edges of the flat wire at the end faces of the coil to remove the bur therefrom while retaining the coating to form insulating ledges which over- 45 hang the edges of the wire. 50

5. The method of producing electro-magnetic coils which consists in treating a sheet of electrically conductive metal to form thereon an insulating coating, cutting said 55 sheet into strips to produce flat wire conductors, winding the flat wire thus produced into a coil, treating the edges of the flat wire at the end faces of the coil to remove the bur therefrom, while retaining the coating to form insulating ledges which overhang 60 the edges of the wire, and finally coating the end faces of the coil with a thin insulating material. 65

6. The method of producing electro-magnetic coils which consists in applying to both sides of a very thin, wide sheet of electrically conductive metal an insulating coating, thereafter cutting the sheet into narrow strips to produce flat wire conductors 70 covered on both sides with an insulating coating and finally winding the flat insulated wires into a coil. 75

In testimony that I claim the foregoing as my invention I affix my signature in the presence of two witnesses, this 29th day of December, A. D. 1914.

CHESTER H. THORDARSON.
